Primary Examiner — Terry Wallace(74) *Attorney, Agent, or Firm* — Polsinelli PC(57) **CLAIM**

The ornamental design for a beverage bottle with lid, as shown and described.

DESCRIPTION

FIG. 1 is a perspective view of the beverage bottle with lid; FIG. 2 is a left side view of the beverage bottle with lid; FIG. 3 is a front view of the beverage bottle with lid; FIG. 4 is a right side view of the beverage bottle with lid; FIG. 5 is a rear view of the beverage bottle with lid; FIG. 6 is a top view of the beverage bottle with lid; and, FIG. 7 is a bottom view of the beverage bottle with lid. The broken lines showing in the figures are included for the purpose of illustrating portions of the beverage bottle with lid that form no part of the claimed design.
